UNITED STATES PATENT OFFICE.

EDGAR WILSON HEISEY, OF NEWARK, OHIO, ASSIGNOR TO A. H. HEISEY & COMPANY, OF NEWARK, OHIO.

DESIGN FOR A TUMBLER.

Application filed November 15, 1923. Serial No. 7,767. Term of patent 14 years.

To all whom it may concern:

Be it known that I, EDGAR WILSON HEISEY, a citizen of the United States of America, residing at Newark, in the county of Licking and State of Ohio, have invented a new, original, and ornamental Design for a Tumbler, of which the following is a specification, reference being had to the accompanying drawing, forming part thereof.

I claim—

The ornamental design for a tumbler, as shown.

EDGAR WILSON HEISEY.
